UNITED STATES PATENT OFFICE.

CHARLES E. KEATOR, OF BROOKLYN, ASSIGNOR TO ROBERT DUNLAP, OF NEW YORK, N. Y.

HAT-POUNCING MACHINE.

SPECIFICATION forming part of Letters Patent No. 338,975, dated March 30, 1886.

Application filed December 10, 1885. Serial No. 185,279. (No model.)

To all whom it may concern:

Be it known that I, CHARLES E. KEATOR, a citizen of the United States, residing at Brooklyn, in the county of Kings and State of New York, have invented new and useful Improvements in Hat-Pouncing Machines, of which the following is a specification.

This invention consists in certain novel features in the construction of a hat-pouncing machine, which are fully pointed out in the following specification and claims, and illustrated in the accompanying drawings, in which—

Figure 1 represents a sectional front view. 15 Fig. 2 is a section on the line *x x*, Fig. 1.

Similar letters indicate corresponding parts. In the drawings, the letter A designates the frame of the machine, on which are mounted the journal-boxes B of the shaft C. Two friction-gears, D and E, connected by a sleeve, F, are mounted on this shaft in such a way that they slide loosely on the same, but turn with it when the shaft is rotated. In one end of the sleeve F is cut a groove, *a*, which is 20 embraced by the forked end of a bell-crank lever, G, having its fulcrum at *b* in a standard, H, while its other end is connected to the foot-lever I, having its fulcrum at *c* in the standard J. The pouncing-block K, to which it is 25 intended to give a revolving motion which may be reversed at will, is mounted on an upright shaft, d, having its bearing in a journal-box, L, secured to the table M. On the lower end of this upright shaft is mounted a 30 friction-gear, N, which can be brought into frictional contact either with the friction-gear D or E, one of which will cause the pouncing-block to revolve in one direction while the other will cause it to revolve in the other.

The sleeve F, which carries the two friction-gears D and E, slides on the shaft C, so that either of these gears may be brought into contact with the friction-gear N, and is operated by the foot-lever I through the bell-crank lever G. A spring, *e*, one of which is secured 40 to the frame A and the other to the bell-crank lever G, imparts to the latter a tendency to keep the friction gears E and N in contact with each other, and also to raise the foot-lever I, so that when this lever is depressed the bell-crank lever will be turned against the action 45 of the spring *e*, and the friction-gears E and N will be separated and the pouncing-block will stand still, or, if the friction-gear D is brought into contact with the gear N, the motion of the 50 block will be reversed. A rack-plate, O, secured to the frame A, serves to hold the foot-lever in either of the above positions.

What I claim as new, and desire to secure by Letters Patent, is—

1. In a hat-pouncing machine, the combination, with the pouncing-block K, of the gears D E N, the shaft C, bell-crank lever G, foot-lever I, and the spring *e*, substantially as 60 shown and described.

2. In a hat-pouncing machine, the combination, with the pouncing-block K, of the gears D E N, the shaft C, the bell-crank lever G, foot-lever I, the spring *e*, and the rack-plate O, substantially as shown and described.

In testimony whereof I have hereunto set my hand and seal in the presence of two subscribing witnesses.

CHARLES E. KEATOR. [L. S.]
